US0D1099661S

(12) **United States Design Patent** (10) **Patent No.:** **US D1,099,661 S**
(45) **Date of Patent:** **** Oct. 28, 2025**

(54) **PLIERS**

(71) Applicant: **Milwaukee Electric Tool Corporation**,
Brookfield, WI (US)

(72) Inventors: **Christopher S. Hoppe**, Midvale, UT
(US); **Mark W. Cors**, St. Francis, WI
(US); **Steven W. Hyma**, Milwaukee,
WI (US); **Grant T. Squiers**, Cudahy,
WI (US); **Michael Stearns**, Milwaukee,
WI (US)

(73) Assignee: **Milwaukee Electric Tool Corporation**,
Brookfield, WI (US)

(**) Term: **15 Years**

(21) Appl. No.: **29/914,952**

(22) Filed: **Oct. 24, 2023**

Related U.S. Application Data

(63) Continuation of application No. 17/313,807, filed on
May 6, 2021, which is a continuation of application
No. 15/089,025, filed on Apr. 1, 2016, now Pat. No.
11,027,399.

Primary Examiner — Deanna L Pratt

(74) *Attorney, Agent, or Firm* — Reinhart Boerner Van
Deuren s.c.

(57) **CLAIM**

The ornamental design for pliers as shown and described.

DESCRIPTION

FIG. 1 is a perspective view of an embodiment of the claimed design;

FIG. 2 is a right side view of the claimed design of FIG. 1;
FIG. 3 is a left side view of the claimed design of FIG. 1;
FIG. 4 is a rear view of the claimed design of FIG. 1;
FIG. 5 is a front view of the claimed design of FIG. 1; and,
FIG. 6 is a top view of the claimed design of FIG. 1.

The ornamental design which is claimed is shown in solid
lines in the drawings.

1 Claim, 5 Drawing Sheets
